EMBOSSED PLASTIC SHEET MATERIAL

Philip Schuss, Columbus, Ohio, assignor to Columbus Coated Fabric Corp., Columbus, Ohio, a corporation of Ohio

Application July 22, 1957, Serial No. 47,011

Term of patent 7 years

(Cl. D87—3)

The figure is a plan view of an embossed plastic sheet material showing my new design.

I claim:

The ornamental design for an embossed plastic sheet material, as shown.
